UNITED STATES PATENT AND TRADEMARK OFFICE
CERTIFICATE OF CORRECTION

PATENT NO. : D1,029,370 S
APPLICATION NO. : 35/513929
DATED : May 28, 2024
INVENTOR(S) : Tommy Asterhed

Page 1 of 1

It is certified that error appears in the above-identified patent and that said Letters Patent is hereby corrected as shown below:

On the Title Page

Item (72) should read:

Inventor: Tommy Asterhed, Sävsjö (SE)

Item (73) should read:

Assignee: Sävjo Plastic AB, Sävsjö (SE)

Signed and Sealed this
Seventeenth Day of June, 2025

Coke Morgan Stewart
Acting Director of the United States Patent and Trademark Office
